STAVE CUTTING MACHINE.

No. 271,290.

Patented Jan. 30, 1883.

UNITED STATES PATENT OFFICE.

FRANZ WITZMANN, OF NEW HAVEN, CONNECTICUT.

STAVE-CUTTING MACHINE.

SPECIFICATION forming part of Letters Patent No. 271,290, dated January 30, 1883.
Application filed October 18, 1882. (No model.)

To all whom it may concern:

Be it known that I, FRANZ WITZMANN, a citizen of the United States, residing at New Haven, in the county of New Haven and State of Connecticut, have invented a new and useful Machine for Cutting Staves; of which the following is a specification, reference being had to the accompanying drawings.

This invention relates to machines for cutting staves for barrels, tubs, and the like; and it has for its object to provide a simple and efficient machine that can be readily adjusted to cut staves of varying length, width, thickness, diameter, or curve.

In the drawings, Figure 1 is a side view of my machine. Fig. 2 is a front end view. Fig. 3 is a top view; Fig. 4, a detail sectional view of the cutting mechanism. Fig. 5 is a like view of the table and its elevating mechanism. Fig. 6 is a transverse sectional view thereof.

Referring to the drawings, A designates a frame of suitable construction, carrying a shaft, B, having crank-wheels C C, which are connected to the rock-arms D D—one at each side of the machine—by pitman-rods E E. Arms D D are arranged on a shaft, F, and carry a cross-head, G, working in the slot H in each arm by means of an adjusting-screw, I, also working in said slot, by operating which the

head may be moved either backwardly or forwardly. From head G extend brackets J, through which work screws K K to resist the thrust of the knife, and also to aid in adjusting the same to elevate or lower said knife.

The knife has its bearing surface on blocks L L at the ends of the cross-head, and are secured to said blocks by screws M, passing through the knife, block, and into the cross-head. The knife and blocks may be readily removed by operating the screws for the substitution of knives and blocks of varying curves.

N is a guide arm or extension, against which the block from which the staves are cut will abut. One of these guides is secured at each end of the cross-head, and are longitudinally adjustable in relation to the machine by means of the screw-bolts O, working in slots P in said guides. The latter are curved and work through corresponding openings, Q, in the table R.

S is a curved spring, arranged back of the

knife, and longitudinally adjustable in relation to the machine, either independently or by being secured to the adjustable guides N.

The table R has a transverse dovetailed groove, T, in which is placed a corresponding base-block, U, for the cutting-knife to strike, so as not to dull its edge. This table is longitudinally adjustable on a bed, V, by means of screws W, working in slots X in the table R and into the bed V. This bed is provided with longitudinal vertical side flanges, X X, for inclosing the table, and also with inclined guides Y on its under side and a vertical slot, Z, at its front. Guides Y work on corresponding inclined guides, A', projecting from a base-bed, B', which latter is also provided with a perforation, C', in its front.

D' is a hand-screw, working through perforation C' into a nut, E', arranged in slot Z, and adapted to move vertically therein. Thus by operating screw D' the bed V, carrying table R, may be elevated or lowered on the guides A'.

In lieu of guide-arms N N, suitable adjustable guide-blocks may be arranged on the table.

The boxes F' F', in which the shaft F works, are vertically adjustable by means of set-screws G', working against their under sides, which adjustment is effected to regulate the knife.

The operation and advantages of my invention will be readily understood. Motion is communicated to shaft B, and from thence transmitted by wheels C C and pitmen E E to rock the arms which carry the cross-head having the transverse curved cutting-knife. The block of wood from which the staves are to be cut is slid under the knife against the guides before the downstroke of the knife, which will cut off the stave, after which the block is fed against the guides, ready for the next stroke of the knife. The staves, after they are cut, pass up back of the knife, and are held by the springs until the stave is pushed out over the cross-head by the next newly-cut stave.

This machine is very simple and convenient, and will operate to cut the staves as fast as the block can be fed under the knife.

I claim as new—

1. In a stave-cutting machine, the cross-head carrying a transverse curved cutter, and a

spring in rear of said cutter to retain the last cut stave against the rear face of the knife while the next stave is being cut, as set forth.

2. The combination, with the cross-head having the removable blocks projecting from its front, and formed with curved front edges, of the removable curved knife resting on the latter, and the adjustable spring secured to the cross-head and projecting up back of the knife, 10 as and for the purpose set forth.

3. The combination, with the cross-head having the brackets projecting from the top, of the curved-face front removable blocks and the curved transverse knife secured to the latter, and provided with screw-threaded shanks 15 working up in said brackets, as set forth.

4. The combination of the frame carrying the drive-shaft, crank-wheels, and pitmen, the longitudinally-adjustable table, the rock-arms 20 journaled on a transverse shaft in rear of the table, and provided with longitudinal slots, the cross-head adjustable by means of screws in these slots, and carrying front blocks, and the knife secured to the latter, as set forth.

5. The combination, with the cross-head having the front blocks and curved knife arranged thereon, and with the table having a curved slot in rear of the knife base-block, of the adjustable curved guide-arm arranged on the cross-head and extending down through the 25 slot, as set forth.

6. The combination of the base-bed having the inclined upwardly-projecting guides and front perforation, the upper bed having corresponding downwardly-projecting guides and 30 front slot, in which vertically slides a nut, and the hand-screw for operating the beds, as set forth.

In testimony that I claim the foregoing as my own I have hereto affixed my signature in 35 presence of two witnesses.

FRANZ WITZMANN.
